ROLLING DAM

Karl Schoen, Wuerzburg, Germany

Application June 11, 1928, Serial No. 284,645, and
in Germany October 11, 1926

4 Claims. (Cl. 61—22)

This invention relates to rolling dams and it is an object of the invention to provide in a dam structure a retaining member forming a tight joint against the bottom in connection with a main body that is mounted to roll on the wall piers.

The invention is furthermore designed to eliminate certain faults and defects notable among which are a tendency to obstruct the surface water passages by mud and to freeze at the joints when the water is low.

Another advantage of the invention resides in that it obviates special shaping of the bottom of the dam to fit the form of the retaining member and further objects are found in simplicity of construction, and low cost of manufacture and installation.

Still another object of the invention is to provide a dam of the above described character which permits of a variation in the retaining level without deepening the dam bottom.

The above and other objects are attained by providing a retaining member, making a tight joint with the bottom, in the form of a shield 25 movably mounted on the main body and pressed downwardly against the dam bottom by the water. The lower end of the retaining member may be connected with the main body by links and the upper end by transmission elements coming into operation as the dam rolls, or the connection between the shield and the body may be made by links additional to the others or by links forming a rigid whole with the shield.

In the accompanying drawings in the various views of which like parts are similarly designated,

Figure 1 represents a front elevation of the dam structure in operative relation to the wall piers;

Figure 2, a cross-sectional elevation of the dam of the first above stated construction, taken in a plane indicated by the line 2—2 in Figure 1, and drawn to a larger scale;

Figure 3, a similar section showing the parts in a different position;

Figures 4 and 5, similar sectional elevations in two different positions, of a dam modified in construction in accordance with the second above described form; and

Figure 6, a similar section of the third stated form of the invention.

Referring first to Figures 2 and 3 of the drawings, the numeral 1 designates the main body of the dam, which is triangular in section and capable of oscillation. The body carries at its ends disks 2 which are supported in a known manner, to roll along the niches 3 of the wall

piers A. The body 1 is provided with a retaining wall 4 the lower end of which, when the dam is in retaining position, is curved cycloidally and at its upper end has a guide wall 5, preferably of wood.

The tight joint at the bottom is made by a shield 6, the lower end of which, carrying the joint or packing beam 7 is secured by links 8 to the body on its side away from the water when in retaining position, and the upper end 65 of which carries bracket socket bearings or abutments 9 which cooperate with bearings or stops 10 mounted on the wall 4.

At the upper end of the shield 6, a spring packing plate 11 is provided, carrying a packing bar 12 70 in contact with the face of the wall 4. A part of the water pressure acting on the shield 6 is transmitted to the retaining wall 4 by the noses 13 of the bearings 9.

In order to relieve the load on the dam operating means, not shown, hooks 14 are provided on the disks 2 to be engaged by yokes 16, carried by vertically adjustable spindles 15.

In the position shown in Figure 1, the dam has its maximum effective height. If this is reduced 80 or ice and drift material is to be let off, the spindles 15 with yokes 16 are first lowered a certain amount. Then the driving mechanism is stopped until the hooks 14 again engage in the yokes 16 as shown in Figure 2.

As the body 1 is lowered, the wall 4 slides over the packing bar 12 and over the noses 13. In consequence of the cycloidal shape of the wall 4, the shield 6 maintains its position in space and the packing plate 11—12 slides on the wall as the latter moves.

In the modified form illustrated in Figures 4 and 5, the main body 17 is also of triangular section, but the shield 18 is at its lower part formed integral with the links 19. In consequence of the rigid construction of the shield with the links, the wall 20 of the body 17 remains entirely free from the water pressure acting on the shield, since said pressure is transmitted from the shield directly to the pivots of the links.

In this form, furthermore, the upper part of the wall 20 represented by the nose 20', in the lowered position of the body 17 (see Figure 5) projects beyond the lower part of the wall, which results in that the water pressure loading the upper part, assists in raising the body.

In the modified form of the invention illustrated in Figure 6, the wall 21 can also be relieved from pressure by connecting the shield 110

with the oscillating body 25 by pairs of links 23-24.

Having thus described my invention, what I claim and desire to secure by Letters Patent is:—

- 5 1. A dam of the character described comprising a shield adapted to engage the bottom of a channel, the shield being pivotally held at one side and free to move at the opposite side, and a relatively movable retaining wall behind the
- 10 shield with regard to direction of flow of water in a stream in which the dam is placed, the free side of the shield being disposed to abut against the retaining wall by the pressure of water in the stream.

15

2. A dam of the character described comprising a shield adapted to engage the bottom of a channel, a retaining wall movable with respect to the shield, and a link having portions respectively mounted on the shield and on the wall and holding same in relative positions.

3. A dam according to claim 2, in which the link is pivotally mounted on the shield and on the wall.

4. A dam according to claim 2, in which the link is fixed on the shield and pivoted on the wall.

KARL SCHOEN.
